UNITED STATES PATENT OFFICE

2,016,267

TAIL GATE RELEASE

Howard Blair Fleming, Scarboro, Maine, assignor
to The Boyd Corporation, Portland, Maine, a
corporation of Maine

Application August 17, 1933, Serial No. 685,625
Renewed March 23, 1935

6 Claims. (Cl. 298—23)

The present invention relates to new and useful improvements in tail gate releases for dump trucks and has for one of its important objects to provide, in a manner as hereinafter set forth, a release of this character which may be conveniently operated from the cab of the truck.

Another very important object of the invention is to provide, in a manner as hereinafter set forth, a tail gate release embodying a novel construction, combination and arrangement of parts through the medium of which said release may be operated regardless of the position of the body of the truck.

Another object of the invention is to provide a tail gate release of the character described which will be simple in construction, strong, durable, highly efficient and reliable in operation, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in vertical longitudinal section through a portion of a truck, showing an embodiment of the present invention mounted thereon.

Figure 2 is a view in vertical transverse section, taken substantially on the line 2—2 of Figure 1.

Figure 3 is a view in top plan of the tail gate release.

Figure 4 is a detail view in vertical section through the slide.

Figure 5 is a detail view in perspective of the lever which is actuated by the slide.

Figure 6 is a plan view, showing a pair of tail gate latches which are actuated by the release constituting the present invention.

Figure 7 is a view in vertical longitudinal section through a modified form of the invention.

Figure 8 is a view in horizontal section, taken substantially on the line 8—8 of Figure 7.

Figure 9 is a view in vertical longitudinal section through another modification.

Figure 10 is a view in top plan of a portion of the modification shown in Figure 9.

Figure 11 is a top plan view, showing one of the tail gate latches and the adjacent operating mechanism therefor in releasing position.

Figure 12 is a view in side elevation of a portion of the mechanism shown in Figure 11, the supporting member being shown in cross section.

Referring now to the drawings in detail, it will be seen that the reference numeral 1 designates a rocker shaft which is journaled longitudinally on the truck frame in suitable bearings 2. Fixed

on the forward end portion of the shaft 1, within convenient reach of the operator sitting in the driver's seat of the truck, is an operating lever 3.

The dump body 4 of the truck is mounted, as usual, on depending brackets 5 which are journaled on the end portions of a shaft 6 which, in turn, is mounted transversely on the rear portion of the truck frame 7. Mounted for reciprocation on the shaft 6 is a slide 8 upon which a collar 9 is rotatably mounted. Fixed on the rear end portion of the shaft 1 is an arm 10 having a slot 11 therein which accommodates a pin 12 which projects from the slide 8, thus operatively connecting said slide 8 to the shaft 1 for actuation thereby.

Depending from the cross member 13 of the truck body is a hanger 14 upon the lower end portion of which a lever 15 is pivotally mounted at an intermediate point. At its lower end the lever 15 is pivotally connected to an upstanding lug on the collar 9, as at 16. As illustrated to advantage in Figure 5 of the drawings, the lower end portion of the lever 15 is offset and bifurcated, the bifurcations straddling the lug on the collar 9. The inner ends of a pair of transverse rods 17 are pivotally connected to the upper end portion of the lever 15, as at 18.

Pivotally mounted beneath the cross member 13 of the truck body is a pair of links 18' to the free forward end portions of which the rods 17 are pivotally connected. The reference numeral 19 designates a pair of longitudinally extending rods which are loosely connected, at their rear ends, to the usual tail gate latches 20. At their forward ends, the rods 19 are pivotally connected by couplings 21 to the links 18' for actuation by said links.

It will thus be seen that when the shaft 1 is rocked in its bearings 2, the slide 8 will be shifted on the shaft 6 by the arm 10 and the pin 12. Movement of the slide 8, of course, actuates the lever 15 which, in turn, actuates the links 18' through the rods 17. The links 18', as will be apparent, swing the rods 19 laterally and at the same time impart longitudinal movement to said rods for actuating the tail gate latches 20. In other words, when the links 18' are swung from the position shown in Figure 3 of the drawings to the position shown in Figure 11, the latches 20 are swung rearwardly on their pivots to gate releasing position. In Figure 1 of the drawings, the tail gate of the truck is indicated at 22. It will thus be seen that the tail gate may be conveniently released by a person sitting in the operator's seat of the truck. It will further be seen that, by reason of the rotary collar 9 on the slide 8, said slide 8 will function to shift or actuate the rods 17 at all times regardless of the position of the dump body 4.

In the modified form of the invention illus-

trated in Figures 7 and 8 of the drawings, the reference numeral 23 designates a bell crank lever which is mounted to swing in a horizontal plane forwardly of the shaft 6 on a suitable supporting bracket 24. A rod 25 operatively connects the bell crank lever 23 to a hand lever 26 mounted in or adjacent the cab of the truck.

One end of the bell crank lever 23 is slotted for the reception of an annular rib 27 which is provided on a slide 28 which is mounted on the shaft 6. The reference numeral 29 designates a lever which is substantially similar in operation to the lever 15 but which includes a forked lower end portion which straddles the rib 27.

It will thus be seen that when the bell crank lever 23 is actuated by the hand lever 26 through the medium of the rod 25, the slide 28 will be shifted on the shaft 6, the slot in one end portion of said bell crank lever 23 which receives the annular rib 27 compensating for the arc described by the bell crank lever. When the slide 28 is shifted on the shaft 6 the lever 29 is, of course, actuated to shift the rods 17. As the truck body 4 is raised or lowered the lever 29 travels about the slide 28, said lever being mounted concentrically with said slide, as will be seen.

In the modification illustrated in Figures 9 and 10 of the drawings, the reference numeral 30 designates a bell crank lever which is mounted to swing in a horizontal plane on a suitable supporting bracket 31. The hand lever 32, located in or adjacent the truck cab, is operatively connected to one end of the bell crank lever 30 by a rod 33. The other end of the bell crank lever 30 is operatively connected to a slide 34 which is mounted for reciprocation on the shaft 6 by a link 35. The slide 34 has projecting therefrom a lug 36 to which the link 35 is pivotally connected. Rotatably mounted on the slide 34 is a collar 37 which is similar to the collar 9. In other respects the modification shown in Figures 9 and 10 is similar in construction to that form of the invention illustrated in Figures 1 to 5, inclusive.

It is believed that the many advantages of a tail gate release constructed in accordance with the present invention will be readily understood, and although the preferred embodiments of the invention are as illustrated and described, it is to be understood that further modifications or changes in the details of construction and in the combination and arrangement of parts may be resorted to which will fall within the scope of the invention as claimed.

What is claimed is:—

1. A tail gate release for dump vehicles of the type including tail gate securing latches, a transverse shaft and a body mounted for tilting movement on said shaft, comprising a slide mounted for reciprocation on the shaft, means for actuating the slide, a lever pivotally mounted on the body for movement therewith about the shaft, means operatively connecting the lever to the slide for actuation thereby, and means operatively connecting said lever to the tail gate latches for moving said latches to operative or inoperative position when the first-named means is actuated.

2. A tail gate release for dump vehicles of the type including tail gate securing latches, a frame, a shaft mounted transversely on the frame, and a body mounted for tilting movement on the shaft, comprising a slide mounted for reciprocation on the shaft, means for actuating the slide, a lever pivotally mounted on the body for movement therewith about the shaft when said

body is tilted, means operatively connecting the slide to the lever, toggles pivotally mounted on the body, rods operatively connecting the links to the lever for actuation thereby, and rods operatively connecting the tail gate latches to the links for actuation by said links when the first-named means is actuated.

3. A tail gate release for dump vehicles of the type including tail gate securing latches, a frame, a transverse shaft mounted on the frame and a body mounted for tilting movement on said shaft, comprising a slide mounted for reciprocation on the shaft, manually operable means on the frame and connected to the slide for actuating said slide, a collar rotatably mounted on the slide, a lever pivotally mounted on the body and pivotally connected, at one end, to the collar, links pivotally mounted on the body, rods pivotally connected, at one end, to the links and at their other ends to the other end of the lever, and rods operatively connecting the tail gate latches to the links for actuation by said links when the first-named means is actuated.

4. A tail gate release for dump vehicles of the type including tail gate securing latches, a frame, a shaft mounted transversely on the frame and a body mounted for tilting movement on said shaft, comprising a slide mounted for reciprocation on the shaft, a rocker shaft journaled longitudinally on the frame, an actuating lever fixed on the rocker shaft, an arm fixed on the rocker shaft, said arm having a slot therein, a pin projecting from the slide and engaged in the slot for connecting said slide to the rocker shaft for actuation thereby, a collar rotatably mounted on the slide, a second lever pivotally mounted, at an intermediate point, on the body and pivotally connected, at one end, to the collar, links pivotally mounted on the body, rods operatively connecting the tail gate latches to the links for actuation thereby when the rocker shaft is actuated, and rods pivotally connected, at one end, to the links and at their other ends to the other end of the said second lever.

5. A tail gate release for dump vehicles of the type including tail gate securing latches, a frame, a transverse shaft on said frame and a body mounted for tilting movement on said shaft, comprising a slide mounted for reciprocation on the shaft, an annular rib on the slide, a bell crank lever pivotally mounted on the frame, said bell crank lever having a slot in one end portion thereof for the reception of the rib for operatively connecting the bell crank lever to the slide, manually operable means on the frame for actuating the bell crank lever, a lever pivotally mounted on the body for movement therewith, said lever including a forked end portion engaged with the rib for connecting said lever to the slide, and means operatively connecting the tail gate latches to the lever for actuation thereby when the first-named means is actuated.

6. A tail gate release for dump vehicles of the type including tail gate securing latches, a frame, a transverse shaft on said frame and a body mounted for tilting movement on said shaft, comprising a slide mounted for reciprocation on the shaft, a bell crank lever pivotally mounted on the frame, a link operatively connecting the bell crank lever to the slide, manually operable means on the frame for actuating the bell crank lever, and means operatively connecting the tail gate latches to the slide for actuation by said slide when said means is actuated.
